UNITED STATES PATENT OFFICE.

LAWRENCE HERBERT WADSWORTH, OF LONDON, ENGLAND.

ELECTRICALLY-OPERATED SWITCH AND THE LIKE.

Application filed June 30, 1922. Serial No. 571,992.

To all whom it may concern:

Be it known that I, LAWRENCE HERBERT WADSWORTH, a subject of the King of Great Britain, residing at 7 Revelstoke Road, 5 Wimbledon Park, London, England, have invented Improvements in and Relating to Electrically-Operated Switches and the like, of which the following is a specification.

This invention relates to electrically operated intermittent switches or make and break devices for electrical circuits to be used as controls or relays, for use in connection with the striking or chiming mechanism of electric and other clocks, for ringing electric bells or sounding alarms for signalling purposes, for flash signs and for other purposes requiring an intermittent and uniform making and breaking of one or more electrical circuits, it has for its primary objects in switches of this type obtaining an instant or impulse contact with quick make and break of the circuit or circuits, adjustability of the rate as well as the duration of the make and break, small current consumption and capability of use in series or parallel with any suitable electric apparatus and continuing to act automatically while electric potential is maintained.

The present invention comprises essentially an electromagnet or solenoid, a rocking armature, an adjustably spring controlled arm carried by said armature which is operated by said magnet or solenoid on completing an electrical circuit in which the magnet or solenoid is included, a transversely arranged spring controlled sliding switch bar adapted to make contact with a contact included in the magnet or solenoid circuit and in some cases carrying or operatively connected with one or more contacts adapted to make contact with other contacts included in one or more electrical circuits which are to be controlled, a single acting dash pot or other suitable mechanism operatively connected to the armature and capable of adjustment whereby the speed of the return movement of the armature under the influence of its spring may be controlled, mechanism for locking the switch bar in either of the two extreme positions it can assume, comprising a pair of spring controlled bell crank levers pivoted on either side of the armature arm, the one arm of each lever carrying a pin adapted to engage one of a

pair of adjustable collars or cams carried on the switch bar and the other arm of the lever engaging one of a pair of adjustable collars mounted on either side of a rod pivoted at its centre to the armature arm, the whole arrangement being such that the armature, being attracted against its spring, first compresses or extends the spring or one of the springs on the switch bar without moving the latter owing to its movement being prevented by the locking mechanism, at or about the end of the movement of the armature, the locking mechanism is liberated allowing the switch bar to suddenly move under the influence of the compressed spring, and so instantaneously make or break the circuit or circuits controlled by said bar, on the return movement of the armature under the influence of its spring—its speed being controlled by the dash pot or other mechanism—the spring, or other spring if two be used, on the switch bar is first compressed or extended without moving the switch bar, and at or about the end of its movement, the locking mechanism is operated allowing the switch bar to again suddenly move in a reverse direction and so instantaneously break or make the circuit or circuits controlled by said switch bar and continuing so to do as long as the potential is maintained in the magnet or solenoid circuit.

A convenient construction of apparatus embodying the present invention is that illustrated on the accompanying drawing in which the figure is a view in plan of the apparatus. Upon a suitable base plate *x* is mounted an electromagnet *a*, the armature *b* of which is carried by the one arm *b*¹ of a bell crank lever.

This lever is capable of rocking on a pivot *b*² and its movement is controlled by an adjustable spring *c* acting through an arm *b*³ carried on the other arm *b*⁴ of the lever. Adjustable stops *a*¹, *a*² are provided to limit the movement of the armature arm *b*¹. In suitable bearings *d* carried by the base plate *x* is free to slide—preferably without rotation a transversely arranged switch bar *e*, the sliding movement of which is controlled by a blade spring *f* carried by the arm *b*⁴ near the pivoting point *b*². It will be noted that the arm *b*⁴ is shown broken away in order to clearly show the spring *f*. The bar *e* has its travel limited by adjustable

stops e^1 engaging the outer faces of the bearings d and in one of the two positions of rest it can assume engages, by one of its ends, with a spring contact g adapted to contact with a contact g^1 , the said contacts g, g^1 being in circuit with the electro-magnet a and any suitable source of electrical energy.

The locking mechanism for the switch bar e comprises a pair of spring controlled bell crank levers h pivoted to the base plate x on either side of the arm b^4 , the one arm of each lever h carries an upstanding knife edged pin i adapted to engage one of a pair of collars or cams k adjustably carried on the switch bar e and the other arm of the lever h is engaged by one of a pair of adjustable collars l carried on a rod m passing freely through said arms. This rod m is pivotally carried by the arm b^4 . On the lower part of the base plate x is fixed a single acting air dash pot n having means for regulating the escape of air from behind the piston thereof. The piston rod n^1 of this dash pot is connected to the free end of the armature arm b^4 . The free end of the rod n^1 is free to slide in a bearing n^2 on the base plate and its travel is limited by an adjustable stop n^3 . The rod n^1 carries a spring contact piece o which can make contact with an adjustable contact p . These contacts are included in an external electrical circuit which it is desired to control. In some cases the rod n^1 may directly operate any desired operating mechanism. The arrangement of the various parts is such that movement of the armature b together with its lever in one direction first slightly flexes the spring f then one of the collars l on the rod m —operated by the arm b^4 —contacts with the one arm of one of the bell crank levers h causing it to move angularly and free the pin i on its other arm from engagement with the collar or cam k on the switch bar e thus allowing the latter to suddenly move under the influence of the spring f and so instantaneously make or break the internal circuit in which the contacts g, g^1 are included as well as making or breaking the external circuit in which the contacts o and p are included, the return movement of the armature with its lever under the influence of its spring o and controlled by the dash pot n will then operate in like manner the movement of the switch bar e in an opposite direction.

I declare that what I claim and desire to secure by Letters Patent is:—

1. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, and locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 60

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 65

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 70

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 75

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 80

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 85

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 90

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 95

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 100

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 105

2. An electrically operated switch, comprising an electro-magnet, a rocking armature, an adjustably spring controlled arm carried by said armature, a transversely arranged spring controlled sliding switch bar, a contact carried thereon, a fixed contact adapted to be engaged by the switch bar contact, electrical connections for said contacts and the magnet to couple them up to a source of electrical energy, a single acting air dash pot having means for regulating the escape of air therefrom and connected to the free end of the armature arm, locking mechanism for the sliding switch bar comprising a pair of spring controlled bell crank levers pivoted on either side of the armature arm, the one arm of each lever carrying a pin adapted to engage one of a pair of adjustable collars or cams carried on the switch bar and the other arm of the lever engaging one of a pair of adjustable collars mounted on either side of a rod pivoted at its center to the armature arm, as set forth. 110
